UNITED STATES PATENT OFFICE.

GEORGE E. SEARING, OF TOWANDA, PENNSYLVANIA.

CHAIR-LOCK.

No. 901,561

Specification of Letters Patent.

Patented Oct. 20, 1908.

Application filed March 21, 1908. Serial No. 422,485.

To all whom it may concern:

Be it known that I, GEORGE E. SEARING, citizen of the United States, residing at Towanda, in the county of Bradford and State 5 of Pennsylvania, have invented certain new and useful Improvements in Chair-Locks, of which the following is a specification.

This invention has for its object a simple, durable and efficient construction of device 10 for holding in firm connection with the floor, the legs of chairs or other articles of furniture, in a manner to permit them to be easily detached and the articles of furniture moved to one side for the purpose of sweeping or the 15 like.

The invention is particularly designed for use in entertainment halls and similar places, although it is obvious that it is also applicable for other uses generally.

20 The invention consists in certain constructions, arrangements and combinations of the parts that I shall hereinafter fully describe and claim.

For a full understanding of the invention, 25 reference is to be had to the following description and accompanying drawings, in which:

Figure 1 is a perspective view of my improved locking device; Fig. 2 is a detail perspective view of one of the parts; Fig. 3 is an inverted perspective view of the other part; and, Figs. 4 and 5 are sectional views.

Corresponding and like parts are referred to in the following description and indicated 35 in all the views of the drawings by the same reference characters.

My improved lock for the legs of chairs or the like comprises two main parts, namely, a keeper plate and a nut arranged for detachable connection therewith, and in the present instance, I have illustrated the keeper as a plate 1 designed to be secured to the floor. For this purpose, the said floor plate is provided at its ends with downwardly offset 45 and outwardly extending apertured ears 2 for the reception of nails, screws or the like. The plate 1 is also formed with a longitudinally extending slot 3 embodying a middle portion 3^a in which the opposite curved walls 50 define arcs of the same circle, the end portions 3^b being contracted and in alinement with each other, as shown. The side edges of the plate 1 are formed with depending flanges 4 which serve to strengthen the floor 55 plate and prevent the same from breaking down upon the imposition of any weight

thereon, the edges of said flanges terminating slightly above the floor or other surface to which the plate is secured, so as to permit a strip to be shoved through the plate between 60 the same and the floor for the purpose of clearing out any dirt that might accumulate therein. At one side wall of the middle portion 3^a of the slot 3, the plate is formed with a depending stop lug 5, as clearly illustrated 65 in the drawing. The lock-nut 6 designed to coöperate with the floor plate 1 is secured to the lower end of the leg of a chair or other article of furniture by means of a screw 7 or other pivot, and said nut is formed, preferably 70 at diametrically opposite points with downwardly offset and outwardly projecting wings 8. The nut 6 is riveted or otherwise secured to turn with a handle 9, which is also mounted on the pivot 7 and which is provided with a disk-like head 10, the margin of which preferably projects beyond the rim edge of the nut 6.

In the practical application of my improved lock, the handle 9 is turned so as to 80 bring the offset wings 8 of the lock-nut 6 into registry with the contracted ends 3^b of the slot 3, and the lock-nut is thus inserted in said slot with the wings 8 lying in planes below the elevated lower face of the floor plate 85 1, and the handle 9 is then turned in the direction where it will lie underneath the chair or other article of furniture, the wings 8 engaging the plate and being turned until one of them abuts against the stop lug 5, whereupon 90 it will be understood that the lock-nut will be held securely in engagement with the keeper or floor plate 1, said stop lug preventing the handle from being turned accidentally far enough to permit the accidental unlocking of 95 the parts.

It is to be particularly noted that the lock-nut 6 is so shaped as to fit snugly, when applied to the plate 1, within the middle portion 3^a of the slot 3. Hence, the parts will 100 always be kept in alinement and the locking and unlocking of the parts will be facilitated. This alinement is also effected by the stop lug 5, as is evident. The head 10 of the handle bears upon the upper face of the keeper 105 or floor plate 1 and takes all of the wear of the parts in the coupling and uncoupling operations. It is also to be noted that the head of the screw 7 or other pivot preferably projects below the offset wings 8 which permits 110 the chair or other article of furniture to slide on the floor on the head of the pivot when

the chair is free from the floor plate so as to avoid possible injury to the lock-nut wings which might occur should said wings rest upon the floor. The clearance between the 5 floor and the underside of the floor plate 1 is such that neither the nut or the head of the pivot will touch the floor, when the parts are locked together.

From the foregoing description in connection 10 with the accompanying drawing, it will be seen that I have provided an improved construction of device of this character which possesses the characteristics of simplicity, 15 ease, and cheapness of manufacture, and efficiency in operation for the purposes for which it is designed.

Having thus described the invention, what is claimed as new is:

1. A lock for chairs or the like, comprising 20 a plate designed to be attached to the floor and formed with an elongated slot, a nut adapted to pass into said slot and arranged for locking engagement therein, and a handle pivotally connected to the chair leg or the

like and formed with a head of larger diameter than the nut and the slot and arranged to rest upon the upper surface of the plate, the nut being secured to said head. 25

2. A lock for chairs or the like, comprising a plate designed to be attached to the floor 30 and formed with an elongated slot and with a depending stop lug contiguous to one wall of the slot, a nut adapted to pass into said slot and formed with offset and outwardly extending wings arranged to lock the nut into 35 engagement with the plate, and a handle provided with a head pivotally connected to the chair leg or the like, and of larger diameter than the nut and the slot, the nut being rigidly connected to the head, as and for the 40 purpose specified.

In testimony whereof I affix my signature in presence of two witnesses.

GEORGE E. SEARING. [L. S.]
